UNITED STATES PATENT OFFICE

141,724

DESIGN FOR A WEIGHING SCALE

Joseph Palma, Jr., Madison, Wis.

Application May 26, 1944, Serial No. 113,761

Term of patent 14 years

(Cl. D52—10)

To all whom it may concern:

Be it known that I, Joseph Palma, Jr., a citizen of the United States, residing at Madison, in the county of Dane and State of Wisconsin, have invented a new, original, and ornamental Design for Weighing Scale, of which the following is a specification, reference being had to the accompanying drawing, forming part thereof.

Fig. 1 is a plan view of a weighing scale showing my new design; and

Fig. 2 is a perspective view of the weighing scale shown in Fig. 1.

The characterizing feature of my invention resides in a weighing scale having a wide sloping base in combination with a telescoping platform having upright side walls of substantially the proportions shown.

I claim:

The ornamental design for a weighing scale, substantially as shown and described.

JOSEPH PALMA, JR.
